(57) **CLAIM**

The ornamental design for a base of blender, as shown and described.

DESCRIPTION

FIG. 1 is a perspective view of the present design;

FIG. 2 is a front view of the present design;

FIG. 3 is a rear view of the present design;

FIG. 4 is a left side view of the present design;

FIG. 5 is a right side view of the present design;

FIG. 6 is a top view of the present design; and,

FIG. 7 is a bottom view of the present design.

The broken lines showing structural features are for illustrative purposes only and form no part of the claimed design.

The dot-dot-dash lines indicate boundaries of the claimed design, and form no part thereof.

1 Claim, 7 Drawing Sheets

FIG. 1
